UNITED STATES PATENT OFFICE.

RUDOLPH HOFFMAN, OF KANKAKEE, ILLINOIS, ASSIGNOR TO SEARS, ROEBUCK AND CO., OF CHICAGO, ILLINOIS, A CORPORATION OF NEW YORK.

OIL BURNER.

Application filed July 10, 1919. Serial No. 309,878.

To all whom it may concern:

Be it known that I, RUDOLPH HOFFMAN, a citizen of the United States, residing at Kankakee, in the county of Kankakee and 5 State of Illinois, have invented certain new and useful Improvements in Oil Burners, of which the following is a specification.

My invention relates to oil burners of the blue flame type, the general aim being to 10 produce a burner of improved construction and arrangement, including an improved manner of mounting the outer combustion tube, an improved construction for the inner combustion tube, and an improved wick 15 stop device.

More specifically, one object of the invention is to provide means for supporting the outer combustion tube so as to enable it to be readily moved from lowered position 20 to a raised position whereby to facilitate the lighting operation.

Another object of the invention is to provide an inner combustion tube in which the upper portion, which is subjected to the 25 extreme heat, is made renewable.

A further object of the invention is to provide a wick stop device of an advantageous character. Wick stop devices of the prior art have comprised stop fingers which, 30 when the parts of the burner are in operative position, are positioned over the wick, so that when this wick is lighted the fingers lie in the flame. This arrangement of the stop fingers is objectional for the reason that 35 they interfere with the burning of the wick, causing it to be consumed unevenly and also decreasing the effectiveness of the flame. A special aim of this invention is to provide a wick stop device of such character that 40 the stop fingers are capable of being withdrawn from their operative position above the wick after having served their purpose in positioning the wick.

The objects of the invention thus generally stated, together with other ancillary advantages, may be attained by the construction and arrangement illustrated in the accompanying drawings forming part hereof in which Figure 1 is a side elevation of 45 a burner embodying the features of my invention. Fig. 2 is a vertical sectional view taken on line 2—2 of Fig. 5. Fig. 3 is a fragmentary detail view showing the

means for supporting the outer combustion tube. Fig. 4 is an under side plan view of 55 the burner, showing the wick stop operating device. Figs. 5, 6 and 7 are horizontal sections taken on the lines 5—5, 6—6 and 7—7 respectively, of Fig. 2. Fig. 8 is a fragmentary skeleton view showing the 60 wick stop device detached. Fig. 9 is a fragmentary sectional view taken on the line 9—9 of Fig. 8. Fig. 10 is a fragmentary elevation showing a detail of construction.

The burner comprises generally, the usual 65 concentric wick tubes 1 and 2 spaced apart to provide an annular space for receiving a wick 3, an outer combustion tube 4 adapted to be seated upon the outer wick tube, and an inner combustion tube 5. 6 indicates a 70 crank arm by means of which the wick stop device including a series of stop fingers 7 is manually operable to move the fingers into position above the wick stop.

The wick tubes 1 and 2 may be of any 75 suitable construction, forming at their lower ends a trough for oil in the usual way. The outer tube 1 carries the usual wick raising and lowering device 8 for the wick 3, and near the upper end of said tube 80 there is provided an annular seat 9 adapted to support the outer combustion tube in its normal or operative position.

The outer combustion tube 4, which may be of any ordinary construction, is movable 85 independently of the inner combustion tube. For this purpose it is provided at its lower end with an annular member 10 adapted to cooperate with a series of stationary pins 11 to support the tube either in a raised or 90 lowered position with reference to the wick 3. Said annular member is fixed upon the outer periphery of the tube 4 and flares outwardly and downwardly so as to clear the annular seat member 9. At its lower edge 95 said annular member 10 is provided with a plurality of depending lugs 12 (herein three in number) equidistantly spaced apart and having inclined edges 13. The pins 11 are mounted upon the annular seat member 100 9 and extend radially therefrom so as to be engaged by the lugs 12. Upon rotation of the outer combustion tube with reference to the pins 11, it will be seen that the lugs 12 will ride upwardly and downwardly 105 upon the pins to raise and lower the tube.

At their lower edges said lugs are provided with stops in the form of hooks 14 adapted to limit the extent of rotation of the combustion tube in one direction.

5 The parts are so proportioned and arranged that when the lugs are supported upon the pins, the combustion tube 4 is supported in raised position with its lower end a substantial distance above the wick. 10 When the lugs are moved off from the pins, said combustion tube is lowered until its lower end rests upon the seat member 9. Such rotation of the combustion tube may be readily accomplished by grasping the 15 handle 15 forming part of the means for supporting the burner drum (not shown). When the combustion tube is in its raised position it will be seen that oil is effectively prevented from creeping upwardly thereon 20 from the wick or the wick tubes. At the same time ready access to the wick is permitted from practically any side of the burner. In order that the annular member shall not interfere with the free passage of 25 air to the wick through the lower end of the outer combustion tube, said member, including the lugs 12, is provided with a plurality of openings 16. Through these openings, when the combustion tube is seated upon the 30 said member 9, air is permitted to pass into the combustion space above the wick.

The inner combustion tube 5 comprises an upper portion 5^a and a lower portion 5^b and is of a diameter slightly less than the inner 35 wick tube 2 so that when supported centrally of said wick tube, the lower end of the combustion tube is spaced from the wick tube. To insure an even spacing of the combustion tube from the inner wick tube, a plurality of 40 bosses 17 are provided at the lower end thereof which is arranged to depend a short distance into the inner wick tube.

The means for supporting the inner combustion tube 5 comprises a central rod 18 entered through an opening in the top wall 19 of the combustion tube and extending downwardly to the lower end of the wick tubes where it is screw-threaded into a U-shaped cross bar 20 fixed at its opposite ends 50 to the wick tubes. Near its central portion, the combustion tube is provided with a perforated partition 21 fixed against vertical movement therein, and bearing between said partition and a nut 22 threaded onto the 55 lower end of the rod 18 is a sleeve 23 surrounding said rod. For the purpose of holding the partition 21 against vertical movement in the combustion tube, I provide a lower end of the lower portion 5^b of the combustion tube. 60

55 The upper portion of the inner combus-

tion tube 5 is in use subjected to extreme heat, so that it frequently becomes necessary to renew the tube because of the gradual destruction of the upper portion thereof. I therefore make the combustion tube in two sections. These sections are of substantially the same diameter and the lower end of the upper section is flared inwardly so as to engage with a seat formed by the shoulder 26 upon the lower section. The two sections 75 are secured together by the rod 18 and sleeve 23, the latter being held against the partition 21 by means of the nut 22.

At the upper end of the lower portion 5^b of the combustion tube 5, I preferably provide a partition 27 having a central aperture 28 of substantial size adapted to permit of a restricted flow of air upwardly into the upper portion of the combustion tube. Similarly in the upper portion of the combustion 85 tube, I provide a restricting partition 29 having a central aperture 30 therein.

It will be seen that the inner combustion tube 5 is normally held against vertical movement by its supporting means, and in spaced relation with reference to the inner wick tube so that oil cannot creep upwardly thereon from the wick. Moreover, the combustion tube may be readily withdrawn as a unit by simply unscrewing the rod 18 from the cross bar 20, and when it is desired to disassemble the sections of the tube this may be readily accomplished by removing the nut 22 and slipping the sleeve 23 from off the rod 18. To facilitate the removal of the rod 18, it has fixed on its upper end a member or head 31 having finger-engaging wings.

To enable the removal of charred portions from the wick, I preferably provide upon the inner combustion tube one or more wick scrapers 32 projecting outwardly therefrom and each comprising one or more upright walls 32^a the lower edges of which are adapted to be engaged by the upper end of the wick when the latter is moved vertically by the device 8. Said walls may be formed integral, angularly disposed relative to each other, and each having a securing flange 32^b by means of which the scraper may be secured to the inner combustion tube. The scrapers are so arranged that upon a rotation of the inner combustion tube with reference to the wick, the latter is rubbed smooth by the lower edge of the scrapers 110 engaging therewith. To permit such rotation of the inner combustion tube, the upper end thereof is freely rotatable relative to the rod 18. 120

The wick stop device comprises a plurality of spring arms 33 formed integral with a ring 34 at their lower ends, which is made of a diameter substantially less than the inner wick tube. At the upper ends of said arms and formed integral there-

with are the wick stop fingers 7. These fingers lie immediately below the partition 21 and project radially outwardly through suitable openings provided in the peripheral wall of the inner combustion tube, and are movable into position directly over the wick 3. It will be observed that the inner combustion tube, with the fingers 7 engaging in the apertures provided therefor in the tube, provides a support for the wick stop device.

The operating means for the wick stop device preferably comprises a member 35 slidable vertically upon the sleeve 23, and a bearing member 36 pivotally connected by means of a plurality of inclined links 37 to the upper ends of the spring arms 33. Said vertically slidable member 35 has at its upper end an annular portion or seat 38 upon which the bearing member 36 is adapted to rest, and at its lower end the member 35 has a perforated disc 39. Said disc is arranged to be slidably engaged by the free end of a central crank 40 of a crank rod 41 operable by means of the crank arm 6. The bearing member 36 may be in the form of a ring with which the lower ends of the inclined links 37 have a pivotal connection, and the upper ends of said links may be connected to the spring arms by means of pins 42 entered through lugs 43 formed integrally with said arms.

The parts are relatively arranged so that when the crank arm 6 is operated to swing the crank 40 upwardly, the latter acting as a cam engages with the disc 39 and forces the member 35 together with the bearing member 36 upwardly, thereby forcing the links 37 toward a horizontal position and the spring arms 33 and fingers 7 thereon outwardly. To position the wick 3, the wick stop fingers must be held manually, by pressure upon the crank arm 6, in their operative position. When the crank arm is released, the action of the spring arms withdraws the stop fingers out of their position above the wick so that when the latter is lighted, the stop fingers are not subjected to the extreme heat of the flame.

The crank rod 41 may be mounted at its opposite ends in the upright portions or legs 44 of the U-shaped cross bar 20 fixed at the lower ends of the wick tubes, the rod being thus disposed immediately above the horizontal portion of the cross bar. To permit of the easy assembling or removal of the crank rod, the opening in the end of the cross bar adjacent the arm 6 is in the form of a notch 45 closed by means of a screw 46. The opposite end of the cross bar is bent to form a stop arm 47 which together with the crank arm 6 normally prevents an endwise movement of the rod. It will be seen that by removing the screw 46, the rod may be swung out of engagement

with the notch 45, whereupon the arm 47 may be withdrawn from its opening in the opposite end of the cross bar.

Preferably the free end of the arm 47 of the crank rod is bent inwardly, parallel to the main portion of the rod to form a stop 48 (Fig. 4) arranged to engage with the lower ends of the wick tubes or limit the movement of the crank arm 6 in one direction, and to limit the movement of said crank arm in the other direction, when the inner combustion tube and wick stop device carried thereby have been removed, a pin 49 may be provided (Fig. 10), which may be mounted at the lower end of the outer wick tube.

In order to hold the annular ring 34 and the spring arms 33 against vertical movement in the operation of forcing the stop fingers 7 into their operative position, and thus prevent the wick stop fingers from frictionally engaging with the upper edges of their respective apertures, I preferably provide a plurality of stop members or braces 50 which may be formed integral with the ring 34 and extend upwardly through the partition 21 into engagement with the partition 27 at the upper end of the lower section of the inner combustion tube. These stop members may, if desired, be reinforced by metallic strips 51 secured upon the braces 50 as by spot welding.

To prevent the too free passage of air upwardly into the inner combustion tube 5 through the space between the annular ring 34 of the wick stop device, and the inner combustion tube, I provide at the lower end of the latter an annular member having an inwardly projecting flange 52.

It will be seen that I have produced a blue flame burner of a very practical character. The outer combustion tube may be supported for movement with reference to the outer wick tube without materially interfering with the free passage of air to the combustion space when the outer combustion tube is in operative position. Should the upper portion of the inner combustion tube become materially injured by reason of the extreme heat to which it is subjected in use, it may be readily removed and a new one substituted. The wick stop device is capable of easy operation and is of an efficient character by reason of the fact that the wick stop fingers are not only capable of being withdrawn from the flame after the wick is lighted but also cannot be left in their extended or operative position by a careless user to the detriment of the fingers 7 as well as to the even and efficient burning of the wick.

While I have herein described the invention with considerable particularity, it will be understood that in the interpretation of the appended claims they are not to be limited

ited except as may be necessitated by the state of the prior art.

I claim as my invention—

1. An oil burner comprising, in combination with a pair of concentric wick tubes, an inner combustion tube having a portion entered within the inner wick tube and supported in spaced relation with reference thereto, an outer combustion tube movable independently of the inner combustion tube, and means for supporting the outer combustion tube in either raised or lowered position with reference to the outer wick tube. 5
2. An oil burner comprising, in combination with a pair of concentric wick tubes, an outer combustion tube mounted upon the outer wick tube, an inner combustion tube having a portion depending within the inner wick tube, a central support within said inner wick tube for said inner combustion tube, and a wick stop device within said depending portion of said inner combustion tube having a stop finger movable radially into and out of the path of movement of the wick guided by said wick tube. 10
3. An oil burner comprising, in combination, a pair of concentric wick tubes having a transverse member at their lower ends, an inner combustion tube having a central stem rigid therewith and detachably mounted on said transverse member, and an outer combustion tube adapted to be seated upon the outer wick tube and movable independently of the inner combustion tube. 15
4. An oil burner comprising, in combination with a pair of concentric wick tubes, an inner combustion tube stationarily supported with reference to the inner wick tube, a wick stop device operatively associated with said inner combustion tube so as to be movable into and out of the path of movement of a wick guided by the wick tubes, and an outer combustion tube mounted upon the outer wick tube for movement independently of said stationary inner combustion tube. 20
5. An oil burner comprising, in combination with a pair of concentric wick tubes and an inner combustion tube, an outer combustion tube having at its lower end a plurality of spaced depending supporting lugs, a plurality of radially extending supports mounted upon the outer wick tube and adapted to support the lugs thereon and spaced apart so as to be capable of receiving the lugs therebetween. 25
6. An oil burner comprising, in combination with a pair of concentric wick tubes, an inner combustion tube of less diameter than the inner wick tube and having a central support rigid with said tube, an outer combustion tube, and means for supporting the outer combustion tube either upon the outer wick tube or in spaced relation with reference thereto. 30
7. An oil burner comprising, in combination with a pair of concentric wick tubes and an outer combustion tube, an inner combustion tube having a central stem, and a transverse member fixed with reference to said wick tubes and having said stem detachably secured thereto. 35
8. An oil burner comprising, in combination, a pair of concentric wick tubes, an outer combustion tube supported for vertical movement with reference to the outer wick tube, an inner combustion tube fixed against vertical movement with reference to the inner wick tube, and a wick stop device carried solely by said inner combustion tube and comprising a plurality of spring arms having fingers movable radially into and out of position above a wick carried by said wick tubes. 40
9. A blue-flame burner having an inner wick tube, an outer wick tube, a perforated combustion tube mounted upon the outer wick tube, and a tube extending axially of and within the inner wick tube and comprising a perforated portion extending above and independent of any connection with the upper end of the inner wick tube. 45
10. A blue-flame burner having two concentric perforated combustion tubes, a wick scraper on one of said tubes, the last mentioned tube being rotatable, and means to hold the last mentioned tube against upward movement. 50
11. A blue-flame burner having in combination with a vertically movable wick and an outer combustion tube, an inner combustion tube adapted to be rotated relative to the outer tube and having a wick-scraping device adapted to project radially therefrom so as to be engageable by said wick in its vertical movement. 55
12. An oil burner comprising, in combination with a pair of concentric wick tubes and an outer combustion tube, an inner combustion tube having a top wall, a supporting stem carried by said wick tubes and having said top wall of the inner combustion tube rotatably mounted thereon, and a plurality of wick stop fingers carried by said inner combustion tube. 60
13. An oil burner comprising, in combination with a pair of concentric wick tubes and an outer combustion tube, an inner combustion tube, a supporting stem rigid with said wick tubes and having said inner combustion tube mounted thereon so as to rotate relative thereto, and a wick scraper fixed on said inner combustion tube and comprising an upright portion, the lower edge of which is adapted to be operatively engaged by a wick carried by said wick tubes. 65
14. An oil burner comprising, in combination, a pair of concentric wick tubes, an inner combustion tube supported entirely free of and in spaced relation with reference to the outer wick tube. 70

- to the upper end of the inner wick tube, an outer combustion tube supported for vertical movement independently of the inner combustion tube, and a plurality of wick stop fingers carried by said inner combustion tube.
15. The combination of a pair of concentric wick tubes, an inner combustion tube mounted for rotation relative to said wick tubes while held against vertical movement, and a plurality of wick stop fingers carried by said combustion tube.
16. The combination of a pair of concentric wick tubes, an inner combustion tube fixed against vertical movement with reference to the inner wick tube, an outer combustion tube mounted for movement with reference to the outer wick tube, and a wick stop device carried wholly by said inner combustion tube and comprising a plurality of radially movable fingers.
17. The combination with a pair of concentric wick tubes and an outer combustion tube, of an inner combustion tube, a wick stop device carried by said inner combustion tube, and means for removably supporting the inner combustion tube in spaced relation with reference to the inner wick tube but normally holding it against vertical movement.
18. An oil burner comprising, in combination with a pair of concentric wick tubes and an inner combustion tube, an outer combustion tube having at its lower end a plurality of spaced dependent lugs, a plurality of pins extending radially outwardly from the outer wick tube and adapted to support the lugs thereon, said pins being spaced apart so as to be capable of receiving the lugs therebetween, and said lugs each having an inclined wall upon which it is adapted to ride up and down upon the pins and each having a stop on its lower end for limiting its movement relative to said pins in one direction.
19. An oil burner comprising, in combination with a pair of concentric wick tubes and an inner combustion tube, an outer combustion tube having an annular member at its lower end and a plurality of radially extending pins on the outer wick tube with which said member is adapted to cooperate to support the outer combustion tube in their raised or lowered position, said annular member having a series of openings therein which permit the passage of air through the outer combustion tube when in its lowermost position.
20. An oil burner comprising, in combination with a pair of concentric wick tubes and an inner combustion tube, an outer combustion tube having an annular member at its lower end, an annular seat on the outer wick tube for said outer combustion tube, a series of depending lugs on said annular member, a series of pins on said annular seat member with which said lugs are adapted to engage to support the outer combustion tube in raised position, said lugs and member having openings therein to permit the free passage of air therethrough into the space between the combustion tubes.
21. An oil burner comprising, in combination with a pair of spaced concentric wick tubes and an outer combustion tube, an inner combustion tube comprising two sections, and means for securing said sections together and supporting them in spaced relation relative to the inner wick tube.
22. An oil burner comprising, in combination with a pair of concentric wick tubes and an outer combustion tube, an inner combustion tube comprising two sections of substantially equal diameter, the lower section being adapted to depend into said wick tube, and means for securing said sections together and supporting them against vertical movement.
23. An oil burner comprising, in combination with a pair of concentric wick tubes and an outer combustion tube, an inner combustion tube formed in two sections and supported with reference to the inner wick tube, and means for detachably securing said sections together.
24. An oil burner comprising, in combination with a pair of concentric wick tubes and an outer combustion tube, an inner combustion tube comprising a lower section of substantially less diameter than the inner wick tube and having an annular seat at its upper end and an upper section substantially equal in diameter to that of the lower section and having an inwardly flared lower end adapted to be seated upon said annular seat of the lower section.
25. An oil burner comprising, in combination with a pair of concentric wick tubes and an outer combustion tube, an inner combustion tube having a partition fixed against vertical movement in its lower end, a central supporting rod having a fixed member on its upper end and depending through the inner combustion tube, a transverse member fixed with reference to said wick tubes into which said rod is adapted to be threaded, a nut on the lower end of said rod, and a sleeve between said nut and said partition, whereby said inner combustion tube is held against vertical movement.
26. An oil burner comprising, in combination with a pair of concentric wick tubes and an outer combustion tube, an inner combustion tube comprising a lower section and an upper section seated thereon, a rod having a fixed head on its upper end and depending through said inner combustion tube, a transverse member fixed upon the lower end of said wick tubes, a nut on the lower end of said rod above said transverse member,

- and a sleeve on the rod bearing between said nut and said upper section whereby to hold the sections together and support them against vertical movement.
27. An oil burner comprising, in combination with a pair of concentric wick tubes, an outer combustion tube, and an inner combustion tube having a series of openings in its peripheral wall, a wick stop device carried by the inner combustion tube and comprising a plurality of spring arms having radially extending fingers at their upper ends extending through said openings, means for preventing vertical movement of said arms so to prevent frictional engagement between said fingers and the edges of their openings, and means for forcing said fingers radially outwardly.
28. An oil burner comprising, in combination with a pair of concentric wick tubes, an outer combustion tube and an inner combustion tube, a wick stop device comprising a plurality of spring arms each having a stop finger movable radially into position over a wick carried by said wick tubes, and means for moving said fingers comprising a vertically movable member and a series of inclined links connecting said member with the upper ends of said arms, and means for moving said vertically movable member.
29. An oil burner comprising, in combination with a pair of concentric wick tubes, an outer combustion tube and an inner combustion tube, a wick stop device comprising an annular ring having a plurality of vertically disposed spring arms, a plurality of wick stop fingers at the upper ends of said arms, a vertically movable member, a plurality of inclined links pivotally connecting said member with said arms, a second vertically movable member bearing against the first movable member, and a crank rod adapted to engage with the second member to move the first member and thereby said fingers radially outwardly against the action of the spring arms.
30. An oil burner comprising, in combination with a pair of concentric wick tubes, an outer combustion tube and an inner combustion tube, a wick stop device comprising a plurality of vertically disposed spring arms, a vertically movable member, a plurality of inclined links pivotally connecting said member with the upper ends of said arms, a second vertically movable member adapted to engage with the first member, a crank rod rotatably mounted at the lower ends of the wick tubes, said second movable member having a disc adapted to be engaged by said crank and a crank arm operable to swing said crank and through said movable members and said links the spring arms outwardly, there being a plurality of stop fingers on said arms adapted to overlie a wick 65 entered between said wick tubes.
31. An oil burner comprising, in combination with a pair of concentric wick tubes, an outer combustion tube and an inner combustion tube, means for supporting said inner combustion tube against vertical movement relative to the inner wick tube, and a wick stop device comprising a plurality of fingers, means whereby said fingers may be manually held in position above a wick carried by said wick tubes, and means normally moving said fingers into inoperative position at one side of the vertical plane of said wick.
32. An oil burner comprising, in combination with a pair of concentric wick tubes, an outer combustion tube and an inner combustion tube, a wick stop device comprising a plurality of stop fingers movable into position above a wick carried by said wick tube but normally withdrawn therefrom, and means for manually holding said fingers in their operative position.
33. An oil burner comprising, in combination with a pair of concentric wick tubes and an outer combustion tube, an inner combustion tube having a central upright rod extending therethrough, a wick stop device comprising a plurality of spring arms each having a radially movable wick stop finger thereon, a member guided for vertical movement by said rod, means including a manually operable crank for moving said member vertically, and means connecting said member with said spring arms whereby an operation of said crank will move said stop fingers radially outwardly.
34. An oil burner comprising, in combination with a pair of concentric wick tubes, an outer combustion tube and an inner combustion tube, a wick stop device comprising a plurality of radially movable stop fingers, a vertically movable member operatively associated with said fingers, means for moving said member in one direction whereby to move said fingers outwardly and spring means adapted to move said member in the opposite direction whereby to cause said fingers to move inwardly.
35. An oil burner comprising, in combination with a pair of concentric wick tubes, an outer combustion tube and an inner combustion tube, a wick stop device comprising a plurality of radially movable stop fingers, a vertically movable member operatively connected with said fingers, and means including a cam adapted to slidably engage said member to move it vertically and thereby said fingers outwardly.
36. A blue-flame burner having a wick tube and an inner combustion tube depending a substantial distance into said wick tube and supported entirely free of and in spaced relation relative to the upper end of said tube.
37. A blue-flame burner having, in com-

bination with a wick tube, an inner combustion tube of less diameter than the wick tube, and means carried by the wick tube and extending upwardly in the combustion tube to support it independently of the upper end of the wick tube.

38. A blue flame oil burner having two concentric wick tubes and two concentric combustion tubes, the inner one of said combustion tubes being stationarily supported with its lower end depending within the inner wick tube but spaced therefrom, and the outer one of the said combustion tubes being mounted for vertical movement independently of the inner combustion tube.

10 39. In a blue flame oil burner, a perforated combustion tube comprising an upper section and a lower section, and means for securing said sections together whereby to 20 permit of the detachment of the upper section from the lower section.

40. A blue-flame burner having, in combination with a pair of concentric tubes adapted to receive a wick, means arranged 25 to be moved into and held manually in position above said wick, said means automatically returning to its inoperative position upon being released.

41. A blue-flame burner having two perforated concentric combustion tubes, the inner one of which is rotatable independently of the outer one while held against vertical movement.

42. A blue-flame burner having two perforated concentric combustion tubes, one of which has a laterally projecting member thereon and is rotatable independently of the other one of said tubes while held against upward movement.

40 43. A blue-flame oil burner, having, in combination with a vertically movable wick, an inner combustion tube, and a wick stop device carried wholly by said tube and comprising a laterally movable finger, a vertically movable operating member for said finger, and means for holding said finger against vertical movement.

44. A blue-flame oil burner comprising, in combination with a vertically movable wick, a laterally movable wick stop finger adapted to be manually held in position above the wick, said finger automatically returning to inoperative position when released.

55 45. A blue-flame oil burner having a vertically movable wick, an inner combustion tube, and a wick stop device comprising a stop finger movable into and out of position above the wick while the combustion tube is 60 in operative position.

46. A blue-flame oil burner having a wick, an inner combustion tube, an outer combustion tube movable independently of the inner tube, and a wick stop device comprising 65 a stop finger movable into and out of po-

sition above the wick while the inner combustion tube is in operative position.

47. A blue-flame oil burner having a wick stop device comprising a laterally disposed finger, a vertically movable member operatively connected to said finger, and manually operable means for operating said member and thereby said finger.

48. In an oil burner, the combination of an annular wick mounted for up and down movement, a pair of combustion tubes mounted in spaced concentric relation in operative association with said wick, the inner one of said tubes having a portion depending into the wick for rigid support therein, a wick stop finger having a support within said inner tube and a portion movable into and out of the path of movement of the wick, said inner combustion tube having an aperture for receiving said portion of the finger, and the outer one of said combustion tubes having supporting means adapted to support it at various elevations with reference to the wick.

49. In an oil burner, the combination of a pair of spaced concentric wick tubes, an annular wick mounted for up and down movement in said tubes, an inner combustion tube having a portion depending within the inner wick tube and fixed with reference thereto, said inner combustion tube having an aperture in its wall located in a horizontal plane a short distance above the wick tubes, a wick stop finger having a part operable through said opening in the inner combustion tube into and out of the path of movement of said wick, an outer combustion tube, and means for supporting said outer combustion tube either in lowered or operative position with reference to said wick or in raised or inoperative position above said wick.

50. In an oil burner, the combination of a pair of spaced concentric wick tubes, an annular wick mounted for up and down movement in said tubes, an inner combustion tube, a wick stop device, means for stationarily supporting said inner combustion tube so as to provide a support for said wick stop device, an outer combustion tube, and means for supporting said outer combustion tube either in lowered or operative position with reference to said wick or in raised or inoperative position above said wick.

51. A blue flame oil burner comprising, in combination, a pair of spaced concentric wick tubes, an annular wick guided by said tubes for up and down movement, a combustion tube fixed with reference to the inner wick tube, and means associated with said inner combustion tube operable into and out of the path of movement of said wick.

52. An oil burner having, in combination with an inner combustion tube, an outer combustion tube and means for supporting

the outer combustion tube comprising an annular member on the lower end thereof having depending lugs with inclined edges, and a series of stationary pins adapted to be engaged by said lugs.

53. An oil burner having, in combination with an inner combustion tube, an outer combustion tube, and means for supporting the outer tube comprising a plurality of 10 depending members each having a recess in its lower edge, and a series of stationary pins arranged to engage in said recesses.

54. A blue-flame oil burner having a central stationary support, and a pair of concentric combustion tubes one of which is 15 rotatably mounted upon the upper end of said support.

55. A blue-flame oil burner comprising, in combination, a wick tube, and a combustion 20 tube having a supporting member secured thereto and adapted to be detachably mounted relative to said wick tube, said combustion tube having a portion depending into the wick tube but in spaced relation relative 25 thereto.

56. A blue-flame oil burner comprising, in combination, a pair of spaced concentric wick tubes, an annular wick guided by said tubes for up and down movement, a combustion tube fixed with reference to the 30 inner wick tube, means operatively associated with said inner combustion tube to limit the upward movement of said wick, an outer combustion tube, and means for supporting 35 said outer combustion tube upon said outer wick tube either in operative or lowered position with reference to said wick or in inoperative or raised position with reference to the wick, said supporting means for 40 the outer tube being operable to vary the position of the tube with reference to the wick by a rotation in either direction of the outer combustion tube with reference

to the inner combustion tube and said wick tubes.

57. In an oil burner, the combination with 45 a pair of concentric wick tubes adapted to receive a wick therebetween for vertical movement, of a wick stop device for limiting the vertical movement of the wick, said device comprising a finger movable radially with respect to said tubes, and means operable from one end of the burner for moving said finger into its operative position over the wick.

58. In an oil burner, the combination with 50 a pair of concentric wick tubes having a wick movable longitudinally therebetween, of means operable from an inoperative position at one side of the wick to an operative 55 position over the wick whereby to limit the upward movement thereof, and means operable from the exterior of the burner for actuating the last mentioned means.

59. In a blue-flame oil burner the combination with a vertically movable wick, of 60 a wick stop member movable into and out of operative position with respect to said wick, a pair of combustion tubes mounted concentrically with respect to each other 70 and said wick, and means extending axially through the burner for actuating said member.

60. In an oil burner, the combination with 75 a vertically movable annular wick, a plurality of wick stop devices located upon the inner side of said wick, and means mounted for up and down movement in the burner and operatively associated with said wick stop devices whereby to effect their movement either from an inoperative position at the inner side of the wick or to an operative 80 position over the wick.

In testimony whereof, I have hereunto set my hand.

RUDOLPH HOFFMAN.
